(57) **CLAIM**

The ornamental design for a pet toy brush ball, as shown and described.

DESCRIPTION

FIG. 1 is a front elevational view of a pet toy brush ball, in accordance with the present design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken lines depict portions of the pet toy brush ball that form no part of the claimed design. The surface between the broken lines and the adjacent solid lines forms no part of the claimed design.
